(57) **CLAIM**

The ornamental design for a bottle, as shown and described.

DESCRIPTION

FIG. 1 is a front elevational view of a bottle showing my new design;

FIG. 2 is a right side elevational view thereof, the left side elevational view being a mirror image;

FIG. 3 is a rear elevational view thereof; and,

FIG. 4 is a top, front, and right side perspective view thereof.

The broken lines shown in the drawings are for environmental purposes only and form no part of the claimed design.
